K. F. W. PETTERSSON

HAIRPIN

Filed June 13, 1923

Fig. 1. Fig. 2.

Inventor:

Karl Fredrik Wilhelm Pettersson

*By George Bayard Jones
Atty.*

UNITED STATES PATENT OFFICE.

KARL FREDRIK WILHELM PETTERSSON, OF EDSBYN, SWEDEN.

HAIRPIN.

Application filed June 13, 1923. Serial No. 645,068.

To all whom it may concern:

Be it known that I, KARL FREDRIK WILHELM PETTERSSON, a subject of the King of Sweden, residing at Edsbyn, in the Kingdom of Sweden, have invented a new and useful Improvement in Hairpins, of which the following is a specification.

Many attempts have been made to produce a hair-pin which will be securely fixed in the hair without being difficult to put in and draw out, but hitherto all such attempts do not appear to have led to the desired result as there are still only to be found in the market the ordinary hair-pins with straight legs or shanks or with wavy legs, which two kinds of hair-pins easily drop out of the hair, as is well known, and will therefore not hold the hair securely.

The present invention relates to a hair-pin which will be securely held in and retain also thin hair and which is at the same time easy to put in and draw out and which does not cause any increased wear on the hair. The present hair-pin is broadly characterized by that at least one shank or leg of the same is bent back, preferably approximately opposite the point of the other shank, inwards between the shanks where it forms a resilient abutment approximately parallel to and cooperating with the other shank. When the hair-pin is put into the hair, the hair can easily enter between the resilient abutment and the cooperating second shank and become gripped between the same, so that the hair-pin is securely held and in its turn holds the hair.

The accompanying drawing shows an embodiment of a hair-pin according to the invention in side view in Fig. 1 and in edge view in Fig. 2.

As illustrated in the drawing, the one leg or shank 1 of the hair-pin is bent back inwards between the shanks so that at the bend it obtains a point 2 approximately opposite the point 3 of the other shank 4. The portion 5 of the shank 1 between the shanks 1 and 4 lies approximately parallel with and close to the shank 4 and forms an elastic or resilient abutment for said shank. As shown in Fig. 1, the point of the shank 4 is bent out from the portion 5 in order to produce an entrance opening for the hair

between the points 2 and 3. When the hair is introduced into said opening the portion 5 springs back from the leg 4 approximately to the position 5' indicated by a dotted and dashed line, depending upon the quantity of hair, and the hair will then of course become gripped between the shank 4 and the portion 5. Said portion 5 lies in the plane of the shanks 1 and 4, as will be evident from Fig. 2, and in order that during its movement the portion 5 shall move in said plane it is provided with a guide which, in the embodiment illustrated, consists of an eye 6 which surrounds the arch 7 of the hair-pin. In order more securely to grip the hair the shank 4 and the portion 5 may be bent into wave shape, as shown in Fig. 1, and it will be understood that such waves may also be made in the shank 1.

It will be understood that the invention is not limited to the embodiment illustrated. The second shank 4 may for instance also be provided with a portion bent inwards and corresponding to the portion 5 which two portions will then cooperate and spring towards and away from one another. The guide for the bent portion or portions may also be made in other suitable manner.

I claim:

1. A hair-pin having at least one of its two legs bent back inwards between the legs and forming a resilient abutment approximately parallel to and cooperating with the other leg.

2. A hair-pin having at least one of its two legs bent back, approximately opposite the point of the other leg, inwards between the legs and forming a resilient abutment approximately parallel to and cooperating with the other leg.

3. A hair-pin having at least one of its two legs bent back inwards between the legs and forming a resilient abutment approximately parallel to and cooperating with the other leg, said resilient abutment lying in the plane of the two legs and being guided in such manner as to be capable of moving only in the plane of said two legs.

4. A hair-pin having at least one of its two legs bent back inwards between the legs and forming a resilient abutment ap-

proximately parallel to and cooperating with the other leg, said resilient abutment lying in the plane of the two legs and being guided at the arch joining the two legs of the hair-pin in such manner as to be capable of moving only in the plane of said two legs.

5. A hair-pin having at least one of two legs bent back inwardly between said legs and forming a resilient abutment approximately parallel to and cooperating with the other leg. ¹⁰

KARL FREDRIK WILHELM PETTERSSON.
